UNITED STATES PATENT OFFICE.

HENRY L. DEMMLER, OF KEWANEE, ILLINOIS.

MOLDING MACHINE.

Application filed August 7, 1920. Serial No. 401,924.

To all whom it may concern:

Be it known that I, HENRY L. DEMMLER, a citizen of the United States, residing at Kewanee, in the county of Henry and State 5 of Illinois, have invented a new and useful Molding Machine, of which the following is a specification.

This invention has reference to molding machines and one of its objects is to provide a structure capable of supporting a flask or molding box with a pattern in position for molding and the flask filled with sand, whereby the sand may be solidified about the pattern by jolting or jarring.

Another object is to provide a fluid pressure actuated molding machine having improved mechanism for controlling the distribution of the pressure medium. Other objects will appear in this specification 20 taken in connection with the accompanying drawings.

The invention preferably comprises a vertical cast body member provided with a reduced cylindrical upper end and a cylindrical sleeve or cylinder, the upper end of which is closed, adapted to reciprocate on the stationary piston, the sleeve being longer than the reduced piston and adapted to strike against a shoulder or anvil at the bottom of its stroke to produce a jarring action. Valves and fluid passages are arranged in the piston, and a power-operated valve actuating mechanism is associated with the valves to control the admission and 30 exhaust of a fluid pressure medium to and from the expansion chamber. The top of the cylinder forms a platen to support flasks carrying a pattern and filled with loose sand. On each down stroke of the cylinder, the jarring action due to sudden 40 stoppage of the sleeve against the anvil will be imparted to the flask, thus compacting the sand about the pattern, and the operation of tamping or ramming by hand is dispensed with.

The invention will be best understood from a consideration of the following detailed description taken in connection with the accompanying drawings forming part 50 of this specification, with the understanding, however, that the invention is not confined to any strict conformity with the showing in the drawings, but may be changed and modified so long as such changes and modifications mark no material departure from the salient features of

the invention as expressed in the appended claims.

In the drawings:

Fig. 1 is a side elevation of the molding machine of the jolting or jarring type.

Fig. 2 is a side elevation of the opposite side of the machine from that shown in Fig. 1 and omitting the driving mechanism.

Fig. 3 is a vertical section on the line 65 3-3 of Fig. 2.

Fig. 4 is a section on the line 4-4 of Fig. 3.

Referring to the drawings there is shown a body structure comprising a base plate 1 70 with uprising supports 2 on opposite sides carrying at the upper ends a block constituting a stationary piston 3 having a shoulder 11 at its lower end joining an anvil. Fitted to the piston 3 so as to move snugly 75 yet freely up and down thereon is a sleeve or cylinder 4 provided with a head 5 and a central stem or rod 6. The head 5 is or may be plane or flat to receive a mold board 7 to sustain a flask or mold box 8 designed 80 to hold a pattern 9 to be embedded in molding sand 10. The sleeve 4 where entered by the piston is of sufficient length to permit the sides of the sleeve to contact with a shoulder or anvil 11, while the head 5 is 85 sufficiently spaced from the top of the piston to provide a chamber 12. The piston has packing rings 13 carried thereby and engaging the inner walls of the sleeve, and the stem 6 has packing rings 14 engaging 90 the walls of a bore 15 through which the stem 6 extends and projects beyond the bottom of the block or piston 3. Extending through the block or piston 3 to one side of the rod 6 is an upright passage 15^a 95 formed at the upper end into a valve seat 16 and at the lower end closed by a bushing 17 carrying a stuffing box or packing gland 18. Extending through the passage 15^a is a valve rod 19 carrying at its upper end a valve head 20 adapted to the seat 16 and at the lower end extending through the stuffing box 18 and terminating in a threaded extension 21 to which nuts 22 are applied. The threaded portion 21 100 of the rod 19 extends through one end of a lever 23 with the nuts on opposite sides and there serving as stops. When the lever 23 is raised the valve 20 is opened and when the lever 23 is lowered the valve is closed.

Leading into the passage 15^a is a branch passage 24 which may receive fluid under

pressure, say compressed air, by way of a pipe 25 conveniently tapped into the piston 3 at an appropriate point.

Extending through the piston 3 on the side of the rod 6 remote from the passage 15^a is another passage 26 extending in an upright direction from a branch passage 27 extending from one side of the piston 3 to the lower end of the passage 26. At the upper end, the passage 26 is provided with a valve seat 27^a for a valve head 28 carried by a valve stem 29 extending downwardly through the bottom of the piston below the passage 26 and at its lower end formed with a shoulder 30 and a reduced continuation 31. At the lower end, below the piston 3, the rod 6 has secured thereto a guide bar 32 through which the reduced end 31 of the valve rod 29 slidably passes. The lower end 20 of the reduced portion 31 of the valve rod 29 is engaged by a lever 33.

Carried by the base plate 1 between the supports 2 is a housing 34 having aligned journal bearings 35, 36, 37 for a shaft 38 extending beyond the end of the housing and there provided with a pulley 39 which may be taken as indicative of any means for applying power to the shaft, whether by way of a belt or by direct connection with an electric motor. On the shaft is a worm 40 meshing with a worm gear 41 on a transverse shaft 42 suitably journaled in the housing and extending to the exterior thereof where the shaft 42 carries cams 43 and 44, each engaging a roller 45 on a respective lever 23 and 33, the cams under-riding the rollers. Any suitable means may be employed to drive the shaft 38, as for instance, a motor 57, preferably of the electric type, mounted on a pedestal 54, as shown in Figure 1, and connected by a belt 52 to the pulley 39.

In using the invention a flask 8 with a pattern 9 and sand 10 therein is placed on the board 7 and the latter is placed on the platen or cylinder head 5, the latter being at its lowermost position with the inlet valve 20 closed and held closed by a spring 46 connected at one end to the lever 23 and at the other end to a fixed part of the structure. Now, a suitable fluid under pressure, such as compressed air, is admitted through the pipe 25 and the passages 24 and 15, the motor 51 is started, and the valves are operated to admit and exhaust air to and from the expansion chamber 12, the inlet valve 20, for example, being opened while the exhaust valve is closed. Quickly thereafter the rotation of the shaft 38 reverses the position of the cams 43 and 44 so that the valve 20 is closed by gravity and the tension spring 46 and the valve 28 is opened, allowing the escape of compressed air from the chamber 12 through the passages 26 and 27 to the atmosphere. The cylinder 4 quickly

responds allowing the platen with the loaded flask 8 thereon to fall until the sleeve strikes the shoulder 11 and the sleeve and parts carried thereby are suddenly stopped. This produces a pronounced jar to the flask and the sand therein compacting the latter about the pattern. The reciprocations of the piston follow each other in rapid succession so that the sand becomes compact and firm as though it had been tamped, except that the compacting effect is materially better than when ordinary tamping is followed.

It is material to the proper action of the driving mechanism that there should be a full and sharp exhaust, which is brought about by providing a relatively large exhaust port 28^a countersunk in the passage 26. Also the passages 26 and 27 are made large whereby no material resistance is offered to the exhaust. The cams 43 and 44 each have opposite concentric portions 47, 48 with portion 47 of greater radius than the portion 48 and these two concentric portions are joined by chord portions 49, 50 in parallel relation. Considering the concentric or curved portion 47 as of greater radius than the portion 48, the lever 23 or 33, as the case may be, will be raised to its greatest extent and the valve controlled thereby will then be open. When the roller 45 is riding upon the curved portion 48 the valve controlled thereby will be closed. The chord portions 49 and 50 permit a sudden drop of the respective lever or a sudden rise thereof, so that the action of opening or closing the valves is quick. The adjustment provided by the nuts 22 permits a regulated compressed air supply to the chamber 12 and the form of the cam 45 engaging the lever 33 provides for the quick and free exhaust.

By providing the valve stem 29 with a reduced end 31 to form the shoulder 30 the latter will be engaged by the bar 32 and open the exhaust valve should it happen that the air is on when the motor is not running.

What is claimed is:

1. In a molding machine, the combination of a body member having ports with valve seats, valves for said ports, a sleeve slidably engaging the body member and raised by fluid pressure introduced through one of said ports, an anvil for arresting the sleeve in its descent, levers for operating said valves and having rollers thereon, and means driven independently of the sleeve and coacting with the rollers for operating the levers.

2. In a molding machine, the combination of a body member having ports with valve seats, valves for said ports, a sleeve slidably engaging the body member, levers for engaging the valves and having rollers thereon, cams for engaging the rollers on the levers, worm gearing for driving the

cams and a motor for driving the worm gearing.

3. In a molding machine, a reciprocable member mounted to move in an upright path and having a head for carrying a charged molding flask, valves for admitting compressed fluid to and exhausting it from the reciprocable member, and means for operating the valves comprising a rockable lever for each valve, a roller carried by each lever, a cam for each roller with the cam having oppositely disposed concentric surfaces of different radii and chord surfaces joining the ends of the concentric surfaces, and means for driving the cams.

4. In a molding machine of the jolting or jarring type, a reciprocable member, inlet and exhaust valves for the reciprocable member with the exhaust valve provided with a stem extension of reduced diameter, means for operating the valves, a rod carried by the reciprocable member and a bar

carried by the rod and traversed by the reduced end of the exhaust valve rod, whereby when the valve operating motor is not 25 running and air is admitted to the reciprocable member the exhaust valve is held open.

5. In a jarring machine, a stationary piston, a cylinder reciprocable on the piston, a head on the cylinder forming a platen, 30 said piston having two fluid passages therein for the admission and exhaust of an expansible fluid, a valve having a stem projecting through the piston arranged in each passage, independent power operated means 35 for opening and closing said valves, and means associated with the cylinder for opening the exhaust valve when the power operated means is idle and the inlet valve is 40 open.

In testimony that I claim the foregoing as my own, I have hereto affixed my signature.

HENRY L. DEMMLER.
